UNITED STATES PATENT OFFICE.

JOHN E. ENDERS AND CHARLES J. ENDERS, OF BERRYVILLE, VIRGINIA.

COMBINATION DOUBLE AND SINGLE DECK FOR STOCK-CARS.

1,171,777.

Specification of Letters Patent. Patented Feb. 15, 1916.

Application filed October 2, 1913. Serial No. 793,033.

To all whom it may concern:

Be it known that we, JOHN EGLESTON ENDERS and CHARLES JENKINS ENDERS, citizens of the United States, residing at Berryville, in the county of Clark and State of Virginia, have invented certain new and useful Improvements in Combination Double and Single Decks for Stock-Cars, of which the following is a specification, reference being had therein to the accompanying drawing.

This invention relates to stock cars and has for its object the production of a simple and efficient adjustable deck for a car which may be either held in a raised or lowered position.

Another object of this invention is the production of an efficient platform or deck for a stock car formed in a plurality of sections to facilitate the operation of the deck so as to allow either one or more sections to be used.

With these and other objects in view this invention consists of certain novel combinations, constructions, and arrangements of parts as will be hereinafter fully described and claimed.

In the accompanying drawings:—Figure 1 is a central longitudinal section through the car. Fig. 2 is a central horizontal section through the car. Fig. 3 is a section taken on line 3—3, of Fig. 1. Fig. 4 is a transverse section through a portion of the deck. Fig. 5 is a detail perspective of one corner of the deck showing the arrangement of the several members of the metallic framework. Fig. 6 is a section taken on line 6—6, of Fig. 2. Fig. 7 is a detail perspective of a portion of one side of the deck showing a portion of one of the hinge side protector plates adapted to coöperate with the edge of the deck. Fig. 8 is a detail perspective of a portion of the frame work of the auxiliary section of the deck showing the closure plate adapted to close the space between the door of the car and the edge of the auxiliary deck. Fig. 9 is a detail perspective of a portion of the channel track coöoperating with the decks. Fig. 10 is a transverse section through a portion of the top of the car showing the manner in which the lifting chains are guided to the winding shaft. Fig. 11 is a longitudinal section through one of the guiding bolts and support therefor. Fig. 12 is a detail perspective of one of the guiding bolts. Fig. 13 is a transverse sec-

tion taken through the winding shaft showing the manner of attaching the chains thereto. Fig. 14 is a detail perspective of the lock used in connection with the winding shaft for holding the winding shaft in a set position. Fig. 15 is a bottom plan view of one of the inner corners of one of the sections of the deck.

It should be understood that the present invention is adaptable both to a newly constructed car especially prepared for receiving the present adjustable deck as well as the old cars which are now in use, as the deck may be readily applied to the old form of cars without materially changing the construction thereof.

It will be seen that by carefully considering the drawings that 1 designates the ordinary stock car which is provided with a pair 75 of winding shafts 2 and 3. These winding shafts 2 and 3 pass through the transverse roof beams 4, and these roof beams are provided with journal portions 5 for constituting efficient journals for the shafts 2 and 80 3. Collars 6 are mounted upon each end of each shaft so as to prevent the longitudinal movement of the shafts 2 and 3 upon the beams 4.

It, of course, should be understood that 85 the car can be constructed in any desired manner and that the journal portions 5 are employed where wooden beams are used for supporting the roof, but in case metal beams are employed the journals 5 may be dispensed with if so desired. A plurality of 90 dividing disks or flanges 7 are carried by each shaft near each end, and these disks are so spaced as to constitute pockets for receiving the lifting chains 8 adapted to be wound 95 thereon. By means of these flanges 7 trackways or pockets will be produced to keep the chains in a correct piled position and prevent the chains 8 from becoming entangled with each other while the decks are 100 being raised and lowered by means of the shafts 2 and 3. The chains 8 are connected to the shafts 2 and 3 by means of eye bolts 9 or any other suitable fastening means, and the chain 8 passing from one side of the car 105 is connected to the top of the shaft whereas a coöoperating chain is connected to the lower face of the shaft so as to cause both chains to be wound uniformly around the shafts 2 and 3 while these shafts are being rotated. 110

Each of the shafts 2 and 3 carries at each end a sprocket wheel over which a sprocket

- chain 10 passes. This sprocket chain 10 also passes over a spring wheel which is operated by a hand wheel 11, and by operating the hand wheel 11 rotation may be imparted to the shafts 2 and 3 through the medium of the chain 10. The hand wheel 11 is keyed to a shaft 12 and this shaft carries a ratchet wheel 13 which is engaged by a pawl 14 to prevent the rotation of the shaft 12 in one direction. It, of course, should be understood that this dog or pawl 14 may be kicked out of engagement with the ratchet wheel 13 when it is desired to operate the shaft in the same direction to which the teeth of the ratchet wheel 13 extend. The shaft 12 is braced by means of a substantially U-shaped bracket 15 as is clearly illustrated in Fig. 1. The bracket 15 is formed integral with a circular plate 16, which plate is riveted or otherwise connected to the end of the car. Each of the shafts 2 and 3 is also provided with a square portion or shank 17 adjacent the sprocket wheel over which the chain 10 passes, and a locking bar 18 is pivotally connected to the side of the car and is provided with a pair of downwardly extending arms 19, which arms are adapted to fit over the square shank 17 of the shafts 2 and 3 to hold the same against rotation when the locking bar 18 is thrown in engagement therewith. A strap 20 is pivotally connected to one of the depending arms 19, and this strap fits over a depending eye 21 carried by the co-operating depending arm 19 for receiving a lock 22, whereby the locking bar 18 will be held against removal from the square shank 17 of the shafts 2 and 3 by unauthorized persons.
- 40 The chains 8 pass from the winding shafts 2 and 3 over the spool-like rollers 23, which spool-like rollers are carried by the inner face of the car so as to constitute guides for causing the chains 8 to have a direct vertical lifting pull upon the respective sections of the deck of the car. The lower ends of the chains 8 are connected to the side edges of the deck of the car by means of eyes or any other suitable or desired fastening means, and bracing chains 24 are also suspended from the central portion of the car and are connected to the central portion of the deck of the car by means of eyes 25, as is clearly illustrated in Figs. 1 and 2.
- 45 50 55 60 65 The bracing chains 24 will limit the downward movement of the sections of the adjustable deck and will assist in supporting the same, thereby relieving considerable of the pressure from the lifting chains 8.
- 60 The car 1 like the majority of cattle cars is provided with an opening upon each side thereof at the center portion to constitute a doorway, and upon one side of each of the doorways, as is clearly illustrated in Figs. 1 and 2, is placed a channel track-way 26 for

receiving the guiding bolts 27 carried by the respective sections of the adjustable deck. A channel plate or track-way 28 is also carried by each corner of the car 1 and the channel portions near the track-way 28 are adapted to receive the corner guiding bolts 29 illustrated in Figs. 1 and 2.

As clearly illustrated in Figs. 1 and 2 the adjustable deck comprises a primary section 30 and an auxiliary section 31. The primary section 30 is shorter than the auxiliary section 31 and only extends longitudinally at one end of the car terminating short of the doorway to facilitate or allow access to be had to one-half of the car when it should be so desired and allow the remaining half or remaining end to be used as a double deck car. Each section of the deck comprises a substantially rectangular frame work formed of angle iron to constitute the side and end beams as indicated at 32, and the corners of these side and end beams or angle irons are connected by means of a triangular reinforcing plate 33, which plate is riveted or otherwise secured thereto. A longitudinally extending channel iron 34 connects the central portions of the end beams of each of the sections of the deck, and each of the channel irons 34 is provided with a projecting lip 35 at each end for constituting an efficient means for allowing the channel iron 34 to be connected to the angle end beams of the respective sections of the deck. The wooden beam 36 is then placed in the channel iron 34 to constitute means to allow the transverse floor boards 37 to be nailed or otherwise secured thereto. The central beam 36 is placed slightly above the lower edge of the channel irons 32 so as to cause the boards 37 to incline slightly toward each edge of the adjustable deck. The ends of the boards 37 are seated within the channel irons 32 as clearly illustrated in Fig. 4. A retaining plate 38 fits along the upper edge of the side and end channel irons 32 so as to retain the ends of the floor boards 37 within the channel irons 32, and bolts 39 are passed through the channel irons 32 and some of the floor boards 37 at spaced intervals to constitute an efficient means for holding the plates in a clamped position over the ends of the floor boards 37.

70 75 80 85 90 95 100 105 110 115 120 125 130 The angle iron which extends transversely of the inner end of the auxiliary section 31 of the deck is provided with an overhanging flange 40 for sealing the opening between the primary section of the platform or adjustable deck. It will, therefore, be understood that the auxiliary section of the deck can not be lowered without first lowering the primary portion 30 of the deck. As above stated the primary and auxiliary deck sections are provided at their inner ends and upon each side thereof with guiding bolts 27, and these guiding bolts are pro-

vided with longitudinally extending grooves 41 in which work the retaining bolts 42 for holding the guiding bolts 27 in their correct position after once having been set. These 5 bolts 42 pass through the frame or angle irons which constitute the frame of the primary and auxiliary deck sections. The outer ends 43 of the bolts 27 are rounded so as to fit in the rounded channels 44' of the 10 guiding channel plate 26. The bolts 27 of the primary and auxiliary deck sections travel in parallel channels formed in the same channel plate 26 as above described and as clearly illustrated in Figs. 1 and 2.

15 The sliding bolts 29 are formed of a similar construction to that illustrated in Fig. 12 and above described, but these bolts 29 extend at an angle of approximately 45 degrees to the deck sections 30 and 31 so as to 20 engage the corner plates 28 as illustrated in Fig. 1. As is clearly illustrated in Figs. 1 and 7 a plurality of protector plates 44' are hinged upon eye bolts 45 and are adapted to overhang the edges of the primary and auxiliary 25 portions of the deck to close up the space between the edge of the deck and the sides of the car, thereby preventing the possibility of an animal getting its foot between the edge of the deck and the car and 30 possibly breaking its limb. The eye bolts 45 fit over the rolled portions 46 formed integral with the closure or protector plates 44' as is clearly illustrated in Fig. 7, thereby constituting an efficient hinge therefor.

35 The protector plates 44' are hinged to the side of the car in between a pair of the longitudinally extending bars 47 constituting the sides and ends of the car, and these 40 protector plates 44' are adapted to fold up between the pair of the bars 47 to facilitate the passing of the deck sections 30 and 31 by the same when being drawn up and also when being lowered to their desired position. To constitute an efficient closure across 45 the end of the auxiliary section 31 and close

the opening made by the door of the car a hinge closure plate 48 is employed which is provided with a beveled edge 49 so as to allow the protector plate 48 to be swung back upon the floor of the auxiliary section 50 55 31 of the deck when it is so desired. By having the beveled edge 49 formed thereon no sharp corner will be produced to injure an animal which might come in contact therewith.

From the foregoing description it will be seen that a quick and very efficient adjustable deck has been provided for a stock car, and that this deck may be at all times carried by the car and placed in the desired 60 position at any time when the double deck is desired to be used. It further should be understood that by means of the guiding bolts 27 and 29 the sections 30 and 31 of the deck may be held against lateral swing in 65 view of the fact that these guiding bolts may be clamped tightly within their channels so as to prevent either the lateral or longitudinal swing of the deck sections.

It, of course, should be understood that 70 this invention may be modified as to its detail mechanical construction without departing from the spirit of the invention.

Having thus described the invention what is claimed as new, is:—

In combination with a stock car, a vertically movable deck, channel plates secured to said car, adjustable bolts secured to said deck and adapted to fit in said channel plates for constituting a guide and holding said 80 deck against swinging movement within said car, and means for raising and lowering said deck.

In testimony whereof we hereunto affix our signatures in presence of two witnesses. 85
